United States Patent Office.

JOHN LESPERANCE, OF ST. LOUIS, MISSOURI.

Letters Patent No. 86,766, dated February 9, 1869.

IMPROVEMENT IN RAILROAD-CAR VENTILATORS.

The Schedule referred to in these Letters Patent and making part of the same.

To all whom it may concern:

Be it known that I, JOHN LESPERANCE, of St. Louis, in the county of St. Louis, and State of Missouri, have invented a new and useful Improvement in Ventilators; and I do hereby declare that the following is a full, clear, and exact description thereof, which will enable others skilled in the art to make and use the same, reference being had to the accompanying drawings, forming part of this specification.

This invention relates to improvements in ventilating-apparatus for houses, cars, &c., whereby it is designed to provide a purified and regulated flow of air, as will be hereinafter more fully described.

Figure 1 represents a front elevation of my improved apparatus, and

Figure 2 is a vertical sectional elevation of the same.

Similar letters of reference indicate corresponding parts.

A represents the inner front face of my improved ventilator, preferably made of sheet-metal, and adapted to be fitted to the window-sash in the place of a pane of glass, by securing the border B in a manner similar to that of securing glass.

Behind the front portion, A, an opening, C, is made to the external atmosphere, for the admission of the same, except in cases where double windows are used, when it communicates with a funnel, D, having an enlarged outer opening, provided with margins or flanges E, for securing to the sash.

Above the opening C, in the back, F, of the ventilator, a perforated bottom or dividing-plate, G, is arranged to support a sponge or other similar substance, through which the entering air must pass.

The sponge may be employed for absorbing the aqueous vapor when the air is too damp.

In the mouth of the air-passage, at the top, I propose to arrange a perforated vessel, H, of sheet-metal,

or other suitable substance for containing charcoal, by which the air, in its transmission through it, will be deprived of all suspended organic matter and unhealthy gas, such as sulphuretted-hydrogen or carbolic-acid gas.

The flow of air through the above-described apparatus may be regulated in a great measure by the capacity of the discharge-passages from the room, such as the chimney-flues, stove-pipe holes, &c., but in case it should pass in too freely at any time, a covering of funnel, I, may be provided for spreading over the top of the perforated vessel H, or other similar means may be employed.

The box may be removed, from time to time, for cleaning the coal of the fine matter deposited in it.

The form and construction may be any substantial deviation from that which I have represented, the essential features of my improvement consisting of the perforated dividing-plates for supporting the sponge and charcoal in a manner to act upon the air, and the means for regulating the flow of air.

Having thus described my invention,

I claim as new, and desire to secure by Letters Patent—

1. The ventilating-apparatus provided with the perforated partition G and perforated box H, and the employment, therewith, of sponge and charcoal, substantially as and for the purpose specified.

2. The combination, with the perforated box H, of the air-regulator I, substantially as and for the purpose specified.

The above specification of my invention signed by me, this 16th day of December, 1868.

JOHN LESPERANCE.
